UNITED STATES PATENT OFFICE.

MAURUS C. RECK, OF ROCHESTER, NEW YORK, ASSIGNOR TO STERLING RANGE & FURNACE CORPORATION, OF ROCHESTER, NEW YORK, A CORPORATION OF NEW YORK.

DESIGN FOR A COMBINATION RANGE.

Application filed June 24, 1926. Serial No. 18,164. Term of patent 7 years.

To all whom it may concern:

Be it known that I, MAURUS C. RECK, a citizen of the United States, residing at Rochester, in the county of Monroe and State of New York, have invented a new, original, and ornamental Design for Combination Ranges, of which the following is a specification, reference being had to the accompanying drawing, forming part thereof.

In the drawing:

Figure 1 is a front elevation of a combination range showing my new design, and Figure 2 is a side elevation of the same.

I claim:

The ornamental design for a combination range, as shown.

MAURUS C. RECK.
